US00D752080S

(12) **United States Design Patent**
Kim et al.

(10) **Patent No.:** US D752,080 S
(45) **Date of Patent:** ** Mar. 22, 2016

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Min Hyuk David Kim**, Seoul (KR);
Min-Jee Jou, Yongin-si (KR)

(73) Assignee: **Samsung Electronics Co., Ltd.,**
Suwon-si (KR)

(**) Term: **14 Years**

(21) Appl. No.: **29/476,333**

(22) Filed: **Dec. 12, 2013**

(30) **Foreign Application Priority Data**

Sep. 3, 2013 (KR) 30-2013-0045300

(51) **LOC (10) Cl.** **14-04**

(52) **U.S. Cl.**

USPC **D14/486**

(58) **Field of Classification Search**

USPC D14/485-495

CPC .. G06F 3/048; G06F 3/0481; G06F 3/048172

See application file for complete search history.

(57) **CLAIM**

We claim the ornamental design for a display screen or portion thereof with graphical user interface, as shown and described.

DESCRIPTION

The sole FIGURE is a front view of a display screen or portion thereof with graphical user interface, showing our new design.

The broken lines in the FIGURE show portions of the display screen or portion thereof with graphical user interface which form no part of the claimed design.

1 Claim, 1 Drawing Sheet
